NOVEL RESILIENT HEEL CONSTRUCTION

Meyer Margolin, Elgin, Ill.

Application March 29, 1941, Serial No. 385,823

1 Claim. (Cl. 36—3)

My invention relates to a novel resilient heel and more particularly my invention relates to the combination of a heel, a leather lift and an interposed resilient layer of rubber-like material which is adapted to resiliently space the lift from the heel and which rubber-like layer extends down through the leather lift into contact with the walking surface.

In the heel of a shoe, two primary problems are presented. First, there is very rapid wear of the lift, which is the external layer of leather attached to the heel, and which must be quite frequently replaced because of uneven wear thereon. The second problem is that of comfort and because of the continuity of rigid structure between the walking surface and the heel, there is considerable jarring and resultant discomfort to the body.

It is the object of my invention to overcome these difficulties by a novel heel construction.

It is a further object of my invention to provide a novel heel having the desirable appearance properties of all leather heels, but with the wearing and comfort properties of a rubber heel.

It is a further object of my invention to provide a heel which has the appearance of a leather heel but in which a resilient layer is interposed completely between the relatively rigid leather portion of the heel and in which the rubber extends into ordinary invisible contact with the walking surface.

These objects are accomplished by the provision of an interposed layer of rubber between the heel base proper and the heel lift.

In order to provide for direct resilient contact with the walking surface, the middle portion of the interposed rubber layer extends down through a corresponding opening in the central portion of the heel lift so that the rubber extends into contact with the walking surface when pressure is brought to bear down thereon. This downwardly extending projection of the interposed rubber layer also is important in that it acts to position and retain the heel lift in engagement with the interposed rubber layer.

I further obtain the desired resilience of the heel construction by the provision of certain openings or air cells within the rubber layer itself.

These and further objects of my invention will be apparent from a consideration of the drawing and the specific description of the figures which here follows:

Figure 1 is a cross-section of the heel of my invention.

Figure 2 is a cross-section of a modified form of my invention in which the resilient interstructure extends up into the heel portion of the interior of the shoe.

Figure 3 is a cross-section along the line 3—3 of Fig. 2.

Figure 4 is a cross-section of a modified form 10 of my invention.

Figure 5 is a cross-section showing a still further modified form of my invention.

Figure 6 is a cross-section showing a modified 15 form of my invention in which the resilient heel structure is in co-action with the resilient heel pad.

Figure 7 is a cross-section taken along the line 7—7 of Figure 6.

Figure 8 is a plan view of the heel pad of 20 Figures 6 and 7.

Figure 1 is a cross-section of the heel of my invention, in which the heel base 70 is shaped with a concave recess 71 which arcs sharply in at 72. A resilient rubber layer 74 is interposed 25 between this heel base 70 and a leather lift 75, the heel lift, rubber layer and heel base being secured together by suitable nails 76 and 77. From the resilient layer 74, there extends 30 through a suitable opening 79 in the heel lift 75 an integral resilient projection 80. The upper inside edge 82 of the heel lift 75 is beveled so that the rubber layer slopes into the projection 80. To provide increased resilience cavities 84 and 85 are located in the under-surface of the 35 resilient layer. These cavities enhance the natural resilience of the rubber layer and accordingly increase the resilience of the combination of the heel lift, rubber layer and heel base.

40 The concave shaping of the under side of the heel base 70 into which the resilient layer fits, not only serves to retain the resilient layer in place, but also acts to enable the rubber of the 45 resilient layer to be pressed down through the lift upon wearing away.

In Figure 2 I show a form of my invention in which a heel base 90 is provided with a central opening 91 extending through the extent of the 50 heel base 90 and in this opening 91 is positioned a rubber core 92 which terminates in a resilient interlayer 93 which resilient interlayer terminates in a downwardly extending resilient projection 94 which resilient projection extends 55 through a suitable opening in the heel lift 95.

The heel lift 95 is secured through the resilient layer 93 to the heel base 90 by suitable nails 97. The resilient core 92 terminates at its upper extremity in a lap 98 which sidewardly extends to a feather edge thinness as at 99. The lap 98 extends over insole 100 of the shoe. The construction here illustrated provides a desirable resilience in that because of the fact that shocks imparted to the heel lift 95 are transmitted to the rubber core 93 and absorbed in the long central core 92. Further there is a complete resilience between the heel of the wearer which rests on the lap 98 so that the heel is actually in direct resilient contact with the walking surface with the core 92 and the resilient projection 94.

In Figure 4 I show a heel base 110 with a central core opening 111 in which is positioned a resilient core 112 which extends from just below the insole 114 down into a resilient interlayer 115 and thence progresses into a downwardly extending projection 116 in contact with the walking surface through the heel lift 117. By means of the sloping shoulders 118 and 119 of the heel lift 117, the shock imparted to the resilient projection 116 is spread through the resilient interlayer 115.

Further, upon wearing away of the extreme end of the projection 116, the rubber interlayer 115 tends to move down under the compression thereof by the lower concave surface of the heel base 110 and this movement is facilitated by the sloped shoulders of the heel lift 117. Because the insole 114 lies in resilient contact with the core 112, there is a resilient connection directly between the insole 114 on which the foot rests and the heel extremity.

In Figure 5 I show a heel base 122 which carries a partial resilient inner core 123. This resilient inner core 123 is integral with a resilient interlayer 124 which extends in the form of a downwardly extending projection 125 into contact with the walking surface through the opening 126 in the heel lift 127. This internal core 123 has the function of absorbing a good deal of shock imparted to the rubber interlayer 124 both through the downward projection 125 and through the heel lift 127. The heel lift 127 in this instance has, as in the examples shown in Figures 1, 2 and 4, a resilient connection only with the heel base through the rubber interlayer.

In Figure 6 I show another form of my invention in which a heel base 130 is provided with a central opening 131 in which is positioned a rubber core 132 which is integral and part of a rubber interlayer 133 which, as above, extends

down in the form of a projection 134 into contact with the walking surface through a heel lift 135. In this instance a heel pad 137, which is provided with suitable perforations 138 and grooves 139, has an integral downwardly extending lug 140, which extends into the opening 131 and meets the resilient core 132 and is positioned in resilient contact therewith.

The lug 140 not only serves to correspondingly position the heel pad 137 in place in the shoe but also affords a direction resilient connection between the heel pad and the walking surface through the resilient core 132 and the projection 134 so as to enhance the entire resilience of the construction. This resilient lug 140 which is integral with the heel pad also tends to absorb the shock of the pressure of the wearer's foot upon the heel pad 137 and this shock is transmitted through the central resilient core.

By providing two separate resilient sections, namely the heel pad and the resilient core and interlayer which are in pressure contact with one another, I provide a facility of assembly and at the same time obtain the new and unexpected results set out hereinabove.

By means of the various constructions set forth above I achieve a new result in this art, namely the provision of a new resilience and comfort in the shoe. By means of the resilient interlayer and resilient shock absorbing core, I provide a direction resilience between the foot and the walking surface which besides absorbing shocks engendered in the ordinary act of walking also increases the wearing qualities of the heel lift.

Although I have given a number of specific examples of the application of my invention, it is to be understood that various modifications will be apparent to those skilled in the art and I, therefore, intend to be limited not by the specific examples here given, but only by the claim hereto appended.

I claim:

In combination a heel base, a heel lift and a rubber-like layer positioned between said heel base and said heel lift; an opening extending through the length of said heel base; a rubber-like core extending through said opening; and a resilient rubber member adapted to contact a wearer's heel, said resilient member having perforations extending therethrough and grooves located on the under side thereof to circulate air in that area; and means for contacting said resilient member and said core.

MEYER MARGOLIN.
